UNITED STATES PATENT OFFICE

2,611,357

PORTABLE BROILING STOVE

Thomas W. Turner, Newport News, Va.

Application March 29, 1949, Serial No. 84,107

1 Claim. (Cl. 126—25)

1

This invention relates generally to the class of stoves and furnaces and is directed to improvements in broilers designed to use charcoal as the heating source.

A principal object of the present invention is to provide a broiler for cooking steaks, chops or meat in other forms or other foodstuffs by the use of charcoal, wherein a novel arrangement is provided for supporting the foodstuff to be cooked upon the door structure whereby when the door is moved to closed position the foodstuff will be automatically shifted into the cooking chamber in position over the burning fuel bed.

Another object of the invention is to provide a broiler of the character stated wherein the door structure is so constructed that when it is moved to opened position to withdraw the cooked food, the oven or cooking chamber will be closed automatically to prevent unnecessary loss of dissipation of the heat.

Still another object of the invention is to provide a broiler of the character stated with novel means for supporting the burning fuel in a manner whereby the fuel may be replenished from time to time as necessary without losing heat from the cooking chamber.

Still another object of the invention is to provide a broiler of the character stated which is designed so that it can be made in a small size for convenient transportation.

The invention will be best understood from a consideration of the following detailed description taken in connection with the accompanying drawing forming a part of the specification, with the understanding, however, that the invention is not to be limited to the exact details of construction shown and described since obvious modifications will occur to a person skilled in the art.

In the drawing:

Figure 1 is a view in front elevation of a broiler structure constructed in accordance with an embodiment of the present invention.

Figure 2 is a vertical section taken substantially on the line 2—2 of Figure 1.

Figure 3 is a horizontal section taken on the line 3—3 of Figure 1 with the door structure in closed position.

Figure 4 is a sectional view corresponding to Figure 3 but showing the door structure in open position.

Figure 5 is a detail section taken substantially on the line 5—5 of Figure 1.

Referring now more particularly to the drawing the numeral 10 generally designates a rec-

2

tangular housing forming the cooking or broiling chamber, such housing comprising a top wall 11, a back wall 12 and side walls 13. The side walls 13 are, as shown in Figure 1, of materially greater length than the back wall whereby to provide supporting legs 13a at the sides of the structure.

Disposed transversely of the lower part of the housing in the plane of the bottom edges of the side walls are horizontal and spaced plates 14, each of which is relatively narrow and has a down turned portion 14a which is disposed against the inner side of a side wall leg forming portion 13a as shown in Figure 1. One of the panels 14 has its forward edge flush with the forward edges of the side walls 13 as shown in Figures 2 and 4 while the other plates 14 are spaced a substantial distance rearwardly whereby are provided the two vent spaces 15 and 16.

20 The area defined by the front edges of the top wall 11, side walls 13 and the forward one of the plates 14 constitutes the door opening which is designated 17. At one side of this door opening is disposed the vertical hinge pin 18 which 15 passes through suitable openings in the top wall 11 and the forward plates 14. This hinge pin 18 maintains in proper swinging position in the opening 17 the door unit which is generally designated 19.

25 The door unit 19 comprises the two walls 20 and 21 joined together in right angular relation as is clearly shown in Figures 3 and 4 and a bottom sector plate 22 which is formed integrally with the bottom edges of the panels 20 and 21 and constitutes the grill plate upon which is placed food to be cooked in the broiler. At the top of the door unit in the angle between the walls 20 and 21 a corner web 23 is formed and the pivot pin 18 passes through this web and 30 through the sector plate 22 to pivotally maintain the door unit in position.

The wall 20 of the door unit constitutes the main door portion for closing the opening 17 when the broiler is in use while the wall 21 constitutes an auxiliary door which closes the opening 17 when the door unit is swung outwardly to uncover the sector plate 22.

35 The sector plate 22 is provided with a plurality of openings 22' to facilitate the upward flow of heat from the fuel supporting grate which is generally designated 24 and which is disposed beneath the opening 15.

To facilitate the swinging of the door unit 19, the door wall 20 carries a knob or suitable type of handle 25 whereby the unit can be swung

in and out as desired. It will also be noted that the grill sector plate 22 rests on and has sliding contact with the top surfaces of the bottom wall panels 14 whereby strain upon the pivot pin 18 is effectively relieved.

The fuel carrying grate 24 is slidably supported below the bottom wall panels 14 by means of the spaced parallel guide strips 26 which are secured to the undersides of the plates 14 and extend from front to rear of the housing and the fuel grate is in the form of a drawer or receptacle having a bottom wall 27 provided with slots or openings 28 and side walls 29 together with front and back walls 30 and 31 respectively.

As shown the side walls are provided with laterally extending flanges 32 which slidably engage upon the spaced guides or tracks 26 to facilitate the sliding of the grate inwardly and outwardly.

In addition to the handle 33 carried by the front wall of the grate to facilitate grasping the same to open and close it, there is provided upon the underside of the rear bottom wall portion 14 a stop strip 34 which limits the inward movement of the drawer.

To facilitate the convenient movement or transportation of the broiler unit the top wall is provided with upstanding ears 35 between which is pivotally engaged a carrying handle or bale 36.

From the foregoing it will be readily seen that there is provided in the present invention a novel type of charcoal broiler or cooking stove which will effectively conserve the heat due to the novel double walled door construction and which may be manufactured of suitable light weight sheet metal and is adapted to be easily and quickly moved or transported from place to place.

I claim:

A portable broiling stove, comprising a substantially rectangular housing having its front and bottom sides open and its side walls de-

pending below the front and rear sides to space the open bottom side above a supporting surface, a pair of spaced, relatively narrow, plates extending transversely of the open bottom side 5 of said housing, leg forming portions downturned from the opposite ends of said plates and contacting the inner sides of the lower portions of said side walls of the housing, a pair of spaced guide elements supported on the lower sides of 10 said plates and extending rearwardly from the front side of the housing, a fuel drawer, constituting a charcoal burning grate, slidably supported by said guide elements and having a perforated bottom and an open top, a door hinged 15 at one side of the open front of said housing, a sector-shaped broiling plate supported from the inner side of the lower edge of said door and having a plurality of slotted openings therein, and a vertical wall rising from the inner of the 20 radial edges of said plate and connecting with the vertical edge of said door adjacent the hinged connections thereof with the housing, said vertical wall acting to close the open front of 25 said housing when said door is moved to fully opened position.

THOMAS W. TURNER.
